(57) **CLAIM**

The ornamental design for a tricycle, as shown and described.

DESCRIPTION

FIG. 1 is a perspective view as viewed from a front side of a tricycle configured in accordance with a preferred embodiment of the present invention;

FIG. 2 is a front view of the tricycle of FIG. 1;

FIG. 3 is a rear view of the tricycle of FIG. 1;

FIG. 4 is a left side view of the tricycle of FIG. 1;

FIG. 5 is a right side view of the tricycle of FIG. 1;

FIG. 6 is a top plan view of the tricycle of FIG. 1;

FIG. 7 is a bottom view of the tricycle of FIG. 1;

FIG. 8 is a front perspective view of the tricycle of FIG. 1, with fewer features shown in broken lines;

FIG. 9 is a front view of the tricycle of FIG. 8;

FIG. 10 is a rear view of the tricycle of FIG. 8;

FIG. 11 is a left side view of the tricycle of FIG. 8;

FIG. 12 is a right side view of the tricycle of FIG. 8;

FIG. 13 is a top plan view of the tricycle of FIG. 8; and,

FIG. 14 is a bottom view of the tricycle of FIG. 8.

The broken lines illustrate environmental structure and portions of a tricycle that form no part of the claimed design.
